UNITED STATES PATENT OFFICE.

BOTHO SCHWERIN, OF FRANKFORT-ON-THE-MAIN, GERMANY, ASSIGNOR TO ELEKTRO-OSMOSE AKTIENGESELLSCHAFT (GRAF SCHWERIN GESELLSCHAFT), OF BERLIN, GERMANY, A CORPORATION.

PROCESS FOR REMOVING LIQUID FROM ORGANIC AND INORGANIC SUBSTANCES.

1,121,409.

Specification of Letters Patent.

Patented Dec. 15, 1914.

No Drawing.

Application filed April 6, 1914. Serial No. 829,952.

To all whom it may concern:

Be it known that I, BOTHO SCHWERIN, residing at Frankfort-on-the-Main, Germany, have invented certain new and useful 5 Improvements in Processes for Removing Liquid from Organic and Inorganic Substances, of which the following is a specification.

The method of removing water or juice 10 from organic and inorganic materials by electro-osmosis is now well known. In previous Letters Patent of the inventor it has been shown in particular that water may be removed from peat in this manner and a 15 comparatively dry peat thus obtained.

Although the product represented a peat 20 of a degree of dryness unattainable by mechanical methods only at disproportionately high cost, it has not been possible hitherto to bring this known process to a practical issue, because the degree of dryness attainable by consumption of a certain amount of energy was not sufficiently high to give the 25 electro-osmotic process commercial value in a wide sense.

The present invention relates to a process 30 by which, without increasing the consumption of energy, a considerable increase in the degree of dryness can be achieved, particularly in the case of peat, but also in the case of other materials of organic or inorganic nature.

It has been found that the electro-osmotic 35 removal of water becomes the more effective the more finely subdivided the material is; that is to say, as the smallness of the particles increases the extent to which the water is removed and the rapidity of the osmosis increase. The present improvement, therefore, consists in comminuting the material for instance the peat to as 40 finely subdivided condition as possible before subjecting it to the electro-osmotic process for removing water. The degree of fineness is limited by commercial considera- 45 tions.

In the chemical treatment of colloids the effect is frequently enhanced by adding to the colloidal body or to a suspension thereof, 50 an electrolyte suitable for bringing the body into the condition of a colloidal solution (sol-condition).

Hitherto the proportion of the added elec-

trolyte has been determined in relation 55 either to the volume or the weight of the substance to which it is to be added. This rule generally leads to unfavorable results since the permissible maximum of added electrolyte is exceeded and the effect thereby diminished. I have found that the maximum permissible addition of electrolyte does 60 not depend on the quantity and the weight of the solid part or on the volume of the liquid in which it is suspended, but the optimum addition of electrolyte depends on 65 the superficies of the dispersoid, that is to say, under otherwise equal conditions on the degree of dispersion of the solid body. The finer the material is divided the more electrolyte is added. If, for instance, one is 70 dealing with particles of a certain size, then a certain proportionate quantity of electrolyte will be needed to ionize the particles, and, if the grinding is continued so far that each particle is divided into four parts, 75 there will be four times as many particles present while the volume as well as the weight of the mass remains the same and therefore in order to ionize all the particles, there must be added a four-fold quantity of 80 electrolyte.

Thus it is the further object of this invention to bring the degree of comminution into such relationship with the amount of added electrolyte, that the maximum of addition for a given degree of dispersion is attained. Here also the limit depends on 85 commercial conditions, namely cost of comminution and cost of electrolyte.

When a body which is to be comminuted, 90 such as peat is subjected to the operation in presence of the electrolyte, the latter has the effect of rendering the comminution much more rapid and thorough. The body is to a certain degree opened up by the electrolyte. This favorable action is of further 95 importance, since, as already stated, the more electrolyte can be added the greater the degree of dispersion of the solid substance. The peat is first roughly ground 100 and then finely ground in ball mills. In this manner there is obtained a considerable increase in the dehydrating effect per unit time and in the content of dry substance in the finished material.

105 The following table relates to treatment

of peat by electro-osmosis during 20 minutes. Intensity of current=5 amperes.

In the following table, the last three columns are headed by the letters A, B and C, these letters meaning respectively, the percentage of water of the peat after grinding; the percentage of water in the peat after the electro-osmotic treatment; and, the amount of electrical energy in kilo-watt hours necessary to produce a thousand kilos of dry peat.

I. 10 kilos peat with 2½ liters water.

2 hours ground.				
15	Volts.	Watts.	% Desiccation.	Amount of water.
	60.4	302	70.0	A. 90.6 B. 68.6 C. 395
				4 hours ground.
	54.0	270	70.9	90.6 67.7 354
20				6 hours ground.
	49.2	246	72.0	90.6 66.4 323

II. To the same mass added 100 ccm. NaOH.

2 hours ground.				
25	51.8	259	72.4	90.2 64.5 327
				4 hours ground.
	48	240	73.0	90.2 63.7 302

III. To the same mass added 200 ccm. NaOH.

2 hours ground.				
30	43.8	219	73.7	90.2 62.8 276
				4 hours ground.
	48	240	73.0	90.2 63.7 302

I have found that the favorable effect of 40 adding an electrolyte is not experienced or only incompletely experienced in the case of many materials. The effect of the electrolyte can now be considerably increased by adding to the mass a colloid body in addition to an electrolyte. Such bodies are, for instance, colloidal silicic acid, humic substance, organic and inorganic colloids. By adding bodies of this kind the effect of the electrolyte is increased. The colloidal body 45 may be added to the mass before the electrolyte is added, or simultaneously therewith. For example, in the treatment of steatite an addition of sodium silicate produces favorable results. In this case the colloid body 50 (colloidal silicic acid) and the suitable electrolyte are united. The former is liberated by hydrolysis and absorbed, whereas 55

the alkali constitutes the electrolyte. In other cases, however, the colloid body may be added as such.

From the tables one can readily see the advantage of the invention. If 10 kilos of peat is ground with 2 and a half liters of water, it is evident that the smaller the particles the less the amount of electrical energy required. If, in two hours of grinding, 395 kilo-watt hours are used, after six hours only 323 additional kilo-watt hours are required. A further improvement is perceived if the grinding takes place in the presence of an electrolyte. If to the above mentioned mixture of peat and water, 100 cubic centimeters of sodium hydrate are added, the same result is obtained with a two hours' grinding as a six hours' 75 grinding without an electrolyte; that is, only 327 kilo-watt hours are required. A six hour grinding with the above mentioned addition of electrolyte needs only an additional 276 kilo-watt hours. An addition of 80 200 cubic centimeters of sodium hydrate gives a further improvement so that the current required for a six hour grinding is reduced from 261 to 216 kilo-watt hours.

What I claim, is:

1. A process for removing water from organic and inorganic substances consisting in subdividing the substances as finely as possible in the presence of an electrolyte suitable for bringing the solid body into sol-condition, and subjecting the substances in sol-condition to the electro-osmotic treatment.

2. A process for removing water from organic and inorganic substances consisting in subdividing substances as finely as possible in the presence of an electrolyte suitable for bringing a solid body in sol-condition and also bringing said finely divided substance in the presence of a colloid body and subjecting the substance to electro-osmotic treatment.

3. A process for removing water from peat consisting in subdividing the peat as finely as possible in the presence of sodium hydrate and subjecting the peat to electro-osmotic treatment.

In testimony whereof I affix my signature in presence of two witnesses.

BOTHO SCHWERIN.

Witnesses:

JEAN GRUND,
CARL GRUND.
